UNITED STATES PATENT OFFICE.

THOMAS B. BENNER, OF CORTLAND, NEW YORK.

GAS-PRODUCER

1,110,372.

Specification of Letters Patent. Patented Sept. 15, 1914.

Application filed March 21, 1914. Serial No. 826,369.

To all whom it may concern:

Be it known that I, THOMAS B. BENNER, a citizen of the United States, residing at Cortland, in the county of Cortland and State of New York, have invented a new and useful Gas-Producer, of which the following is a specification.

The present invention relates to improvements in gas producers, and more particularly to that type of gas producer used for making illuminating gas in which retorts are heated containing the fuel, the particular gas producer herein set forth being designed for obtaining gas from bituminous coal or slack, one object of the present invention being the provision of superposed communicating retorts wherein a plurality are filled from a single filling opening at the top of the producer, thus facilitating the filling of the retorts and rendering such operation more simple.

A further object of the invention is the provision of a plurality of superposed retorts having centrally disposed inlets aligned so that the fuel is delivered from and through the top retort to the bottom retort, there being means disposed at the end of each retort for preventing the backing of the fuel against the removable ends and at the same time constituting a gas directing means for permitting the gas generated in the respective retorts to be properly delivered to the final directing and cleaning means.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a vertical central sectional view through a complete gas producer embodying the present invention, such section being taken on line 1—1 of Fig. 2. Fig. 2 is a cross section taken approximately on line 2—2 of Fig. 1. Figs. 3 and 4 are detail views illustrating the closures of the retorts.

Referring to the drawings, the numeral 1 designates the casing of the producer which is preferably made of brick, the usual

form of generator 2 being provided therein having a plurality of waste gas and flue directing outlets 3 outletting to the upper part of the retort containing compartment of the producer. Air is led from the bottom at the opening 5 and follows the direction of the arrows combining at the port 6 with the gas from the generator 2 to combine therewith and properly heat the space containing the retorts, such gas following the line of the arrows and outletting at one side at 7 and at the opposite side at 8, the flue 9 being the final outlet for the waste gas at the left side of the apparatus, as shown in Fig. 2.

Disposed between the cross walls 10 and 11 in the retort carrying portion of the producer, are a plurality of retorts 12, having the centrally disposed fuel charging inlets 13 which are in communication at a similar point with the superposed retorts 14, said retorts 14 being disposed between the partition 11 and the crown partitions 15 of the retort chamber. Each retort 14 is provided with the charging inlet 16, which is disposed above and coaxial with the corresponding charging ports 13 of the retorts 12. Thus when the fuel is directed through the inlet 17 sealed by the gas tight closure 18, from the charging car C, and operated by a poker through the poke holes 21, the same will assume the lines as indicated in Fig. 1, the lower retort 12 being the one primarily charged.

In order to properly seal the outer ends 19 of the respective retorts 12 and 14, such outer ends 19 are projected beyond the brick work of the producer and are sealed by the covers 20, each cover being provided with the closure controlled poke hole 21 so that the upper level of the fuel may be maintained by the introduction of a poker therethrough. Connected to and projecting inwardly from the inner face of the respective closures 20, is an arm or arms 100 22, which carry the partition or plate 23, the inner face of which is lined with fire brick or the like, such member 23 providing a channel between its face and the closure 20 for the passage of the gas from the respective retorts. By this arrangement it will be seen that the gas will not be forced to follow a circuitous route which is the usual custom in producers of this character, but will pass into the respective ends of 118

the retorts 12 and 14, that leading from the respective ends of the retort 12 entering the short couplings 24-24' passing into the space between the plates 23 and the covers 5 20 of the retort 14 and finally into the couplings 25-25' into the lead pipes or conduits 26.

Thus with this construction, the gas has a shorter distance to travel being led from 10 both ends of the retort and thus prevents the formation of lamp black and carbon, the gas retaining the light hydro-carbon matter in suspense to remain in the gas and thereby prevent the formation of naphthalene and 15 free carbon that usually is deposited in the tar and the pipes through which the hot gas passes to the respective hydraulic mains 28-28' into which the directing terminals 27-27' are disposed and placed in communication. The pipes 24-24' and 25-25' 20 are connected by expansion joints, so as to remain tight at all times and yet permit the necessary contraction and expansion due to the heat.

25 With this structure of retort and the arrangement of the superposed retorts, it will be noted that it is possible to charge them solid and thus contain a larger charge of coal than is usually the practice, the larger 30 charge of coal preventing the rising gas vapor from the coal to come in contact with any open space or heated walls of the retorts, which tend to remove the valuable hydro-carbons and deposits therefrom and 35 cause the formation of carbon as an obstruction to reduce the capacity of the retort. The present retorts are so designed and charged in the center, as to prevent the carbon from forming as the lines of admitting air when the retorts are discharged 40 passes along the walls of the retorts and escapes through the charging hole. In this process of manufacture, the gas as delivered from the coal is not held under pressure 45 or over the heated retort walls, but is delivered at a shorter distance and at normal atmospheric pressure. The resulting by-products thus produce a better and more solid coke, and the tar is free from the 50 lamp black, which thus increases the yield of gas and ammonia liquor.

In operating the present producer, and in charging the retorts, the same are charged from the center, the lower retort being filled 55 first, the coal being leveled through the respective poke holes 21. The closures at the proper time being removed and the coke discharged by a pusher into a cooling system and in transit as it is crushed, screened 60 and formed in sizes for use.

What is claimed is:

1. A gas producer, having a plurality of superposed retorts, such retorts being in communication with each other through a 65 fuel charging port, and the upper retort

being provided with a main charging port coaxial with the port of the lower retort.

2. A gas producer, having a plurality of superposed retorts, such retorts being in communication with each other through a 70 fuel charging port, and the upper retort being provided with a main charging port coaxial with the port of the lower retort, and the respective ends of the retort being in communication with each other and constituting a gas receptacle and directing means.

3. A gas producer, having a plurality of superposed retorts, such retorts being in communication with each other through a 80 fuel charging port, and the upper retort being provided with a main charging port coaxial with the port of the lower retort, and the respective ends of the retort being in communication with each other and constituting a gas producer and directing means, a pipe leading from the gas receptacle and directing means of the upper retort at each end thereof, and a hydraulic main 85 into which said pipe leads.

4. A gas producer, having a plurality of superposed retorts, such retorts being in communication with each other through a fuel charging port, and the upper retort being provided with a main charging port 90 coaxial with the port of the lower retort, and means disposed in each end of the retorts forming a gas receiving chamber, the chamber of the upper retort being in communication with a similar chamber of the 95 retort below.

5. A gas producer, having a plurality of superposed retorts, such retorts being in communication with each other through a fuel charging port, and the upper retort 100 being provided with a main charging port coaxial with the port of the lower retort, means disposed in each end of the retorts forming a gas receiving chamber, the chamber of the upper retort being in communication with a similar chamber of the 105 retort below, a pipe led from the chamber of the upper retort, and a hydraulic main in communication with such pipe.

6. A gas producer, having a plurality of 110 superposed retorts, such retorts being in communication with each other through a fuel charging port, and the upper retort being provided with a main charging port coaxial with the port of the lower retort, a 115 removable closure for both ends of each retort, and a partition disposed adjacent the closure of each retort to prevent the packing of the fuel against the closure, and to form a gas receiving and directing chamber between the partition and the closure.

7. A gas producer, having a plurality of superposed retorts, such retorts being in communication with each other through a fuel charging port, and the upper retort 120

being provided with a main charging port coaxial with the port of the lower retort, a removable closure for both ends of each retort, a partition disposed adjacent the closure of each retort to prevent the packing of the fuel against the closure and to form a gas receiving and directing chamber between the partition and the closure, the chamber of the upper retort being in communication with the chamber of the lower

retort, and a pipe lead from the chamber of the upper retort for carrying the gas thereaway from.

In testimony that I claim the foregoing as my own, I have hereto affixed my signature in the presence of two witnesses.

THOMAS B. BENNER.
